HYDRAULIC DRIVE

Albert A. Fiddler, Renton, Wash., assignor of one-half to George K. Huff, Renton, Wash.

Application February 29, 1944, Serial No. 524,501

7 Claims. (Cl. 264—12)

1

The device forming the subject matter of this application is adapted to be used to govern the movement of any desired part, for example, the butterfly valve of an internal combustion engine, through the instrumentality of relatively rotatable parts, actuating and actuated by a liquid contained in a casing.

The invention aims to supply novel means for producing the desired movement in the governing part, to supply novel means for varying that movement at the will of an operator, and to furnish novel means whereby oil leakage will be avoided.

The device is capable of many uses other than in connection with an internal combustion engine, as those skilled in the art will understand readily.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in elevation, a device constructed in accordance with the invention, yoked operatively with a structure to be governed;

Fig. 2 is a sectional view taken longitudinally of the casing, parts remaining in elevation;

Figs. 3, 4, 5 and 6 are transverse sections taken, respectively, on the lines 3—3, 4—4, 5—5 and 6—6 of Fig. 2, it being presupposed that the observer is looking in a direction of the arrows in that figure;

Fig. 7 is a section on the line 1—1 of Fig. 6;

Fig. 8 is a circumferential section taken through one of the guards and adjacent parts.

In carrying out the invention, there is provided a fixed cylindrical casing 1, preferably provided with an integral end wall 2 and with a detachable end wall 3. The end wall 2 carries a gland 4, and the end wall 3 is provided with a gland 5.

A driving shaft 6 is journaled in the gland 4 and may be rotated by any appropriate means, indicated conventionally at 7. A driven or governor shaft 8 is mounted to rock in the gland 5.

An arm 9 is secured to the shaft 8, for adjustment circumferentially of that shaft, and is ad-

2

justably pivoted, as indicated at 10, to a connecting rod 11 or its equivalent. A counterweight 12 is adjustable longitudinally of the rod 11, and is held in adjusted positions by a set screw 14 or the like.

5 The device forming the subject matter of this application may be used for various purposes, but in Fig. 1 there is shown a portion 15 of the manifold of an internal combustion engine, a valve shaft 16 being mounted to rock in the manifold. To the shaft 16 is attached an arm 17, which is pivoted at 18 to the connection 11.

An impeller 19 is secured to the shaft 6, and an impeller 20 is secured to the shaft 8. Each impeller comprises a plate-like body 21, the area of which is substantially equal to the cross section of the interior of the casing 1, and radial, laterally projecting vanes 22 carried by the body. The vanes 22 of the impellers 19 and 20 project toward each other. In its periphery, each of the impeller bodies 21 is supplied with transverse notches 23, each of the notches being located, preferably, midway between two adjoining vanes 22.

25 A liquid, such as oil, not shown in the drawings, is contained within the casing 1, and may be introduced thereto upon removal of a closure screw 24, carried by the casing.

The shaft 8 has longitudinal movement in the gland 5, as well as rotation therein. The longitudinal movement of the shaft 8 enables the impeller 20 to be spaced at different distances from the impeller 19, and, thus, the effect produced on the impeller 19 by the impeller 20 may be varied. The movement of the impeller 20 and the shaft 8 to the right in Fig. 2 is governed by a stop, which is adjustable, the stop preferably embodying a screw 25, threaded into the end wall 3 and held in place by a lock nut 26. A ball 27 is mounted to rotate in the inner end of the screw 25, and forms an anti-friction element, for engagement with the body 21 of the impeller 20.

30 Closely adjacent to the end wall 2 of the casing 1 is disposed a sealing device 28. The sealing device 28 fits closely but rotatably in the casing 1. The sealing device 28 comprises a semi-circular part 29 and a semi-circular part 30.

The semi-circular part 29 is of hollow construction, but the semi-circular part 30 is preferably of plate-like form. The parts 29 and 30 of the sealing device 28 are pivotally connected, as shown at 31, adjacent to the periphery of the sealing device.

Near its periphery, the sealing device 28 has ports 32 therethrough. The ports 32 are covered

by guards 33 which open circumferentially of the shaft 6. A retractile spring 34 is located in the part 29 of the sealing device 28, one end of the spring being anchored at 35 to the part 29, the opposite end of the spring being anchored at 36 on the edge of the part 30. The sealing device 28 grips the shaft 6 and rotates therewith. The guards 33 are placed on the inner surface of the sealing device 28, that is, upon the surface which faces the impeller 19.

Adjacent to the end wall 3 of the casing 1 is located a sealing device 37. The sealing device 37 is constructed much like the sealing device 28 and parts hereinbefore described have been designated by numerals already used, the numerals being primed.

The sealing device 37 does not rotate with the shaft 8, the shaft having longitudinal movement with respect to the said sealing device. The sealing device 37 is provided with an opening 38, through which the adjusting screw 25 passes. The sealing device 37 may be held against rotation by any desired means supplemental to the screw 25. For example, a wedge retainer 39 may be introduced through the wall of the casing 1, into engagement with the sealing device. The sealing device 37 is not provided with the ports 32 and the guards 33 of the sealing device 28.

In practical operation, when the shaft 6 and the impeller 19 are rotated, there is a reversed flow of oil or other liquid in the casing 1, between the impeller 19 and the sealing device 28, as shown by the arrows to the left of the impeller 19 in Fig. 2. There is also a circulation of the oil in the direction of the impeller 20, as indicated by the arrows to the right of the impeller 19 in Fig. 2.

Rocking movement is imparted to the shaft 8 by the impulse which the impeller 20 receives from the impeller 19. The arm 9 is actuated, and motion is imparted to the valve shaft 16 or other part by the connecting rod 11 and the arm 17. The weight 12 acts as a counterpoise, offsetting the torque on the shaft 8 to a considerable extent.

The governing effect produced by the impeller 20 may be regulated by moving the screw 25 longitudinally, the ball 27 having a bearing against the body 21 of the impeller 20. The notches 23 in the bodies 21 of the impellers 19 and 20 tend to relieve excessive pressures which may be created in the casing 1, due to operation at excessive speed.

The guards 33 are connected along their forward ends and along their sides to the sealing device 28, but are open at their rear ends. Noting the arrow on the shaft 6 in Fig. 2, and comparing Fig. 8, it may be said that the guards open in a direction counter to the direction of rotation of the shaft 6.

Thus there is created within the guards 33 and in the region about them, on the side of the sealing member 28 that is disposed toward the impeller 19, a reduction of pressure which tends to draw through the ports 32 any liquid which may leak to the left of the sealing device 28, and such liquid will be returned through the ports 32 to the space between the sealing device 28 and the impeller 19.

The sealing device 37 tends to prevent oil from leaking about the shaft 8 into the space between that impeller and the end wall 3. But, since the impeller 37 does not rotate, the ports 32 and the scoops 33 of the sealing device 28 are omitted.

The device forming the subject matter of this application is simple in construction but will be found thoroughly advantageous for the ends in view and set out hereinbefore.

Having thus described the invention, what is claimed is:

1. In a hydraulic drive, a casing, a driving shaft journaled in the casing, a driven shaft mounted for rocking movement in the casing, and for longitudinal sliding movement therein, toward and away from the driving shaft, opposed impellers carried by the shafts and located in the casing, and means under the control of an operator for limiting the longitudinal movement of the governor shaft in a direction away from the driving shaft, the area of each impeller being substantially equal to the internal cross section of the casing, each impeller having circumferentially spaced pressure-relief openings therethrough, the openings being disposed closely adjacent to the inner surface of the casing.

2. In a hydraulic drive, a casing, a driving shaft journaled in the casing, a driven shaft mounted for rocking movement in the casing, and for longitudinal sliding movement therein, toward and away from the driving shaft, opposed impellers carried by the shafts and located in the casing, and means under the control of an operator for limiting the longitudinal movement of the governor shaft in a direction away from the driving shaft, each impeller comprising a disk-like body and vanes projecting laterally from the body, the vanes of one impeller projecting toward the vanes of the other impeller, the body of each impeller being supplied with circumferentially spaced pressure-relief openings therethrough, each opening being disposed approximately midway between two adjoining vanes.

3. In a hydraulic drive, a fixed casing, a driving shaft journaled in one end of the casing, a driven shaft mounted rotatably in the opposite end of the casing, opposed impellers carried by the shafts and located in the casing, a sealing member connected to the driving shaft to rotate therewith and disposed close to said one end of the casing, the sealing member fitting closely but rotatably in the casing and having circumferentially spaced transverse ports therethrough, guards on that surface of the sealing member which is disposed toward the impeller of the driving shaft, each guard being extended about one of the ports, each guard opening at one end in a direction counter to that in which the driving shaft is rotated, the guards constituting means for creating suction in the ports to withdraw liquid which may have leaked into the space between the sealing member and said one end of the casing, and means for imparting rotation to the driving shaft, in the direction stated.

4. A hydraulic drive constructed as set forth in claim 3, and wherein the sealing member comprises approximately semi-circular parts, a pivotal connection between said parts, and a retractile connection between said parts and causing them to grip the driving shaft.

5. A hydraulic drive constructed as set forth in claim 3, and wherein the sealing member comprises approximately semi-circular parts, a pivotal connection between said parts and a retractile connection between said parts and causing them to grip the driving shaft, one of said parts being hollow, the retractile connection being housed therein, the connection being anchored to one edge of the other of said parts.

6. A hydraulic drive comprising a fixed cylin-

drical casing, a driving shaft journaled in one end of the casing, a driven shaft mounted rotatably in the opposite end of the casing and for longitudinal movement therein, impellers in the casing and secured to the shafts, a first sealing member disposed closely adjacent to said one end of the casing and connected to the driving shaft for rotation therewith, a second sealing member disposed closely to said opposite end of the casing, both sealing members conforming in area to the internal cross section of the casing, the driven shaft passing movably through the second sealing member, means for fixing the second sealing member against movement with

the driven shaft, and means under the control of an operator for limiting the longitudinal movement of the driven shaft toward and away from the driving shaft, said means passing adjustably through the second sealing member.

7. A hydraulic drive constructed as set forth in claim 6, and wherein each sealing member comprises approximately semicircular parts, a pivotal connection between said parts, and a retractile connection between said parts and causing the sealing members to embrace the respective shafts closely.

ALBERT A. FIDDLER.
